UNITED STATES PATENT OFFICE.

PETER JARDINE, OF HESPELER, ONTARIO, CANADA, ASSIGNOR TO A. B. JARDINE & CO., LIMITED, OF HESPELER, ONTARIO, CANADA.

COLLAPSIBLE TAP.

1,362,800.

Specification of Letters Patent. Patented Dec. 21, 1920.

Application filed October 30, 1919. Serial No. 334,388.

To all whom it may concern:

Be it known that I, PETER JARDINE, a subject of the King of Great Britain, of the town of Hespeler, county of Waterloo, 5 Province of Ontario, Canada, have invented certain new and useful Improvements in Collapsible Taps, of which the following is a specification.

My invention relates to improvements in collapsible taps, and relates more particularly to a tap of this class which can be used for threading parallel and tapered holes or bores, and in the present application I shall disclose a form of collapsible tap for doing 10 the same class of work as the collapsible tap disclosed in my co-pending application Number 334,387, filed Oct. 30, 1919. The tap disclosed in the present application will be rotated and fed to the work which will be 15 held stationary; whereas in the said co-pending application the tool is held stationary and the work rotated and fed thereto.

Since the tool disclosed in this present application rotates, it is desirous that the same 20 be set without stopping the machinery, and without danger to the operator, and, therefore, the principal object of this present invention is to modify the construction of certain elements in my said co-pending application to effect the object in view.

In the following specification, coupled 25 with the drawings forming part thereof, I shall set forth the movements necessary to effect the object in view, and the preferred 30 means used to secure these movements, and what I claim as new will be pointed out in the claims forming part of this specification.

Figure 1 is a side elevation of my tool, 35 certain parts being shown in section. In this view, the cutters are expanded. Fig. 2 is a vertical longitudinal section on the line 2—2, Fig. 1, through portion of the tool, showing the cutters collapsed. Fig. 3 is a 40 vertical cross section on the line 3—3, Fig. 2. Fig. 4 is a front elevation of the tool, with portion of the tripping plate removed. Fig. 5 is a side elevation of the major portion 45 of the front end of the tool body. Fig. 6 is an elevation of the front end of the tool body. Fig. 7 is a plan view of the cam-sleeve. Fig. 8 is a 50 vertical cross section on the line 8—8, Fig. 7. Fig. 9 is an elevation of the front end of the plunger head which carries the cutters. Fig. 10 is an end elevation of one of

the cutters of the tap. Fig. 11 is a plan view of the cam stop, and Fig. 12 is a side elevation thereof. Fig. 13 is a side elevation, partly in section, of the keeper used in tapping parallel holes or bores. Fig. 60 14 is a side elevation, partly in section, of the keeper used in tapping tapered holes or bores. Fig. 15 is a side elevation, partly in section, showing my tool adapted for tapping tapered holes or bores. Fig. 16 is a 65 vertical cross section on the line 16—16, Fig. 15, and Fig. 17 is a vertical section through a suitable adjusting nut for the keeper.

In the drawings, like characters of reference refer to the same parts. 70

In the tool disclosed in my said co-pending application, the cutters are automatically collapsed, as is the case in this present disclosure, but the means used to reset the tap essentially project beyond one side of 75 the tool, and since the said tool is held stationary, the said re-setting means is manually operated. In the present disclosure, the re-setting operation is effected by the operator holding a certain element, known 80 as a keeper, stationary for a certain length of time so that during the rotation of the tool, the cutters will be expanded.

At the outset it will be understood by one skilled in the art, that this present tool, as 85 well as the tool disclosed in the co-pending application, can be used for cutting right-hand and left-hand threads.

1 is the tool body, and the same comprises a shank 2 which is designed to be mounted in 90 any suitable chuck (not shown) so that the tool may be rotated. 3 is the head of the tool body, and this head is provided with a plurality of radially-disposed slots 4, of any desired number, opening into the bore 5. 95 Mounted to operate within the bore 5 is a plunger 6, which is provided with a head 8. The said head is preferably provided with a plurality of radially-disposed members 9 which are located opposite the slots 4. 10 100 These cutters, together with the members 9, or equivalent means, carried by the plunger 6, form a collapsible tap. In order that the said cutters may be expanded 105 and contracted as the plunger 6 is moved longitudinally in the bore 5, I provide any suitable means whereby the movement of the members 9 is transmitted to the cutters 10. The preferred means for this purpose 110

consists in providing each member 9 with a flange 11 which fits a correspondingly-shaped groove 12 formed in each cutter 10. 13 is a flange forming part of each cutter 10, 5 and each of these flanges operate in one of the grooves 14 formed in the members 9. It will be observed upon referring particularly to Figs. 2 and 9 that the members 9 are disposed at an angle to the longitudinal axis 10 of the tool and that they converge toward the forward end of the tool. The inner edges of the cutters 10 are also similarly disposed.

The cutters 10 are retained in place by 15 any suitable means such as a plate 14' secured to the outer end of the head 3 by any suitable means such as screws 15. The said plate closes the forward ends of the slots 4, and it will be seen upon referring particularly to Fig. 2 that the said cutters are co-extensive with the length of the said slots 4, 20 and have sliding movement with the walls thereof.

16 is a lever which extends through aligned 25 slots 17 and 18 formed in the shank 2. These slots open into the bore 5. The said lever also extends through a slot 19, formed in the plunger 6, and is pivoted to the head 3 of the tool body, by any suitable element such as a 30 pin 20. The slots 17 and 18 are tapered substantially as shown so as to allow for the necessary movement of the lever 16.

21 is an extension spring, or equivalent means, coupled after any suitable manner 35 to the end of the plunger 6. This spring 21, or equivalent means, exerts power continually to withdraw the plunger 6 and its head 8 into the tool body, and in order to maintain the said plunger and head 8 in the position 40 illustrated in Fig. 1, I use any suitable means such as a pin 22 which is in alinement with one of the slots 4. This pin is held in a hole 23 formed in the head 3 of the tool body, and which hole opens into the slot 17.

45 In the position of the parts illustrated in Figs. 1 and 2, the pin 22 abuts against one of the members 9 in the head 8, and is held against the lever 16 which, in the position illustrated in Fig. 1, is locked against movement. It will, therefore, be understood that in the position of the said parts as shown in Fig. 1, the pin 22 prevents the spring 21 from withdrawing the plunger 6 and head 8 into the tool body.

50 As before mentioned, the cutters 10 are for the purpose of tapping a parallel hole or bore, and as the work (not shown) is held stationary, the tool is rotated and advanced toward the work. When the work is about 55 fully tapped, the tripping plate 24 contacts therewith, and actuates the parts hereafter described, so as to collapse the cutters 10. This tripping plate is preferably provided with a cylindrical flange 24', which embraces the cam-sleeve 28 which embraces the

tool body. The said tripping plate 24 is adjustably coupled to the cam-sleeve 28 by any suitable means, and the preferred construction for this purpose comprises a pair of threaded studs 25 tapped into the sleeve 70 28. These studs extend through slots 26 formed in the flange 24', and are provided with flanges 27, which span the said slots and come in contact with the flange 24' so as to hold the said flange in adjusted position. 75

30 is a keeper (see Figs. 1, 2, and 13) to be used with the tool when tapping parallel holes or bores, and this keeper embraces the tool body. At certain times, the cam-sleeve 28 houses the inner portion of said keeper. The said keeper is provided at its inner end with a spiral cam-face 29, the highest point of which terminates in a flat face 29' which is disposed substantially at right angles to the longitudinal axis of the tool. When the parts are in the position illustrated in Fig. 1, the flat face 29' of the cam-face 29 is in the path of movement of the lever 16, and it therefore follows that the thrust of the pin 22 against the lever 16 is opposed by the keeper 30. 31 is a stud carried by the keeper 30 and positioned behind the face 29' of the cam-face 29. This stud at certain times is located in the circumferential groove 31', formed in the inner side of the cam-sleeve 28. 32 and 32' are slots formed in the cam-sleeve 28, and opening each into the other, thus forming a common slot of two portions of 100 the same length, and these portions or slots occupy the same angular position to the longitudinal axis of the said sleeve. The end 85 of the slot 32 is formed with the sides 86 thereof substantially parallel to the longitudinal axis of the cam-sleeve 28, as shown clearly in Figs. 1, 7, and 15. 105

27 is a curved cam-stop secured by any suitable means such as pins 27' in the groove 31' in the position illustrated particularly 110 in Fig. 1 so as to form a stop which abuts against the stud 31 so as to compel the keeper 30 to rotate with the tool at certain times.

The stud 31 is normally in alinement with 115 the end 85 of the slot 32 and rests against one end of the cam-stop 27 and so soon as the tripping-plate 24 comes in contact with the work (not shown) this tripping-plate is moved backward and carries with it the 120 cam-sleeve 28. By reason of the movement the end 85 of the slot 32 allows, the cam-stop 27 is moved out of contact with the stud 31, and since the walls *aa* of the slot 32 are brought into contact with the said stud, 125 the keeper 30 is rotated in the direction indicated by arrow past the lever 16 until the shoulder 29'' of the cam-face 29 escapes by said lever when the spring 21 or equivalent means is permitted to act and so collapse the 130

cutters. This collapse of the cutters occurs only when the work is fully tapped. At the time of the completion of the movement just described, the stud 31 is located substantially at the position 32" of the slot formed in the cam-sleeve 28.

Now in order to re-set the tool, that is, expand the cutters 10, the operator grasps the keeper 30 by hand through the medium 10 of the flange 30' thereof, holding this keeper stationary. The tool continues to revolve to the right in this embodiment, and through the co-action between the stud 31 and the walls of the slot 32', the cam-sleeve 28 is 15 moved back to normal position during which movement the lever 16 travels up the spiral cam-face 29 until it occupies the position illustrated in Fig. 1, thus through the pin 22 constantly in contact therewith forcing forward the head 8 of the plunger 6 and expanding the cutters 10. Immediately the stud 31 is passed from the slot 32', it is located within the circumferential groove 31' 20 and through the rotation of the cam-sleeve 28, the cam-stop 27 is in due course brought 25 into contact with the stud 31, thus forcing the keeper 30 to rotate with the tool.

Upon referring particularly to Figs. 1 and 11, it will be seen that the axis of the 30 stud 31 is in alinement with the longitudinal center of the cam-stop 27, and that one end of this cam-stop is provided with a beveled corner 27" over which the stud 31 passes when the cam-sleeve 28 (which carries this 35 cam-stop) is forced backward.

Screwing on the threaded portion 33 of the tool-body is an adjusting nut 34 which is interlocked after any suitable manner as shown at 35 with the keeper 30 so as to allow 40 for the described movement of the said keeper. This adjusting nut 34 is locked in position by any suitable means such as the set screw 36 (see Fig. 2 particularly) and while it functionates to retain the keeper 30 45 against longitudinal movement, it is interlocked therewith as before described, so that the tap may be adjusted to tap holes or bores of different diameters within its capacity.

50 In turning the adjusting nut to the left, the keeper 30 will be drawn backward thus permitting movement of the lever 16 under pressure from the pin 22 which, in turn, is moved by pressure thereagainst of the head 55 8 brought into action through the elastic means 21. The described movement of the said head will withdraw the cutters 10 the required amount.

From Fig. 17 it will be seen that the interlocking means 35 of the nut 34 allows of the interfitting of the nut with the keeper 30.

50 a are the inner ends of the slots 4, and it is the space formed by these inner ends in which the members 9 pass when the tap is 55 collapsed. b is a key mounted in the shank

2, and the same travels in a key-way c formed in the cam-sleeve 28: the construction just described, or its equivalent, is that which conveys movement to the cam-sleeve 28 from the shank 2 of the tool-body. 70

The preferred means for coupling the spring 21 to the shank 2, is to suitably couple the bolt 39 to said spring, and to countersink the head 40 of said bolt in the outer end of the shank 2. There is nothing new 75 in the construction just mentioned, but it will be understood that this is a convenient way of adjusting the tension of the said spring, which is the preferred type of elastic means employed for the purpose set 80 forth.

My tool as just described is adapted for tapping parallel holes or bores. Now to adapt it for tapping tapered holes or bores I must use tapered cutters 10' (see Fig. 15) 85 and these are placed on the plunger head 8 after the plate 14' is removed. Obviously, the cutters 10' must be withdrawn as the tapping of the tapered hole or bore proceeds, and to time the proper withdrawal of 90 the said cutters, the tripping plate 24 must be moved into substantially the position shown in Fig. 15 before the tool is put to work. By loosening the studs 25, the adjustment of the said plate 24 can be effected, 95 and after adjustment said studs are tightened up.

It logically follows that before the cutters 10' can be withdrawn, the lever 16 must be given a backward movement simultaneously with the required movement of said cutters. Now to effect this movement, a modified form of keeper 30" (see Figs. 14 and 15) must be substituted for the keeper 30. This change in elements occurs at the 100 same time the cutters 10' replace the cutters 10. The normal position of the lever 16 in respect of the keeper 30" is shown in Fig. 15, and it will be observed that the said lever rests against the apex of the beveled face d 110 of this keeper. As the cam-sleeve 28 is moved backward, through the co-action between the stud 31 and the walls of the slot 32, the keeper 30" is rotated in the direction of the arrow, thus moving the tapered face 115 d of the cam-face dd in respect of the lever 16, thus allowing for the continuous withdrawal of the said cutters 10' during the tapping operation. Since from the commencement of the tapping of the cutters 10' 120 they must be gradually withdrawn the tapered face d will be longer than is the equivalent face when tapping parallel holes or bores, and by the time the shoulder de of the keeper 30" escapes the lever 16, the cutters 10' will have performed their work, and will be completely withdrawn through the operation of the spring 21 and the parts actuated thereby.

It will of course be understood that the 130

cutters 10' are re-set after the manner before described.

This specification discloses a durable, yet inexpensive tool and any parts that are broken can be readily replaced without much trouble.

Upon referring particularly to Fig. 7, it will be obvious that by reason of the provision of the circumferential groove 31' in 10 the cam-sleeve 28, the walls *aa* of the slots 32 and 32' beyond where they open into the said circumferential groove will be deeper than the walls of the said slots where they open into the circumferential groove 31' (as 15 shown at *cc*) so as to provide for the necessary engagement between the stud 31 and the walls of the said slots.

Various changes in details of construction may be made without departing from 20 the spirit of my invention.

What I claim is,

1. A tool of the class described comprising a bore-provided body provided with a head having a chamber extending longitudinally thereof; a plurality of cutters mounted in said head; a plunger mounted in said bore and adapted to co-act with said cutters so as to move them radially inwardly and outwardly; elastic means for actuating said 30 plunger; means associated with said tool and designed to lock said plunger in forward position so as to hold said cutters in outward position, comprising a keeper mounted on said body and provided at its 35 inner end with a spiral cam-face; a lever pivoted to said body and operating through slots formed therein which open into the bore thereof, said lever extending through a slot formed in said plunger and normally 40 resting in contact with the top of said cam-face; means interposed between said plunger and said lever whereby said plunger is held in forward position, and means co-acting with said keeper and adapted to be moved 45 longitudinally of the tool as said means comes in contact with the work so as to rotate said keeper to move the top of said cam-face past said lever to release said lever and unlock said plunger and permit of the collapse of 50 said cutters through the action of said elastic means.

2. A tool of the class described comprising a bore-provided body provided with a head having a chamber extending longitudinally 55 thereof; a plurality of cutters extending longitudinally thereof; a plurality of cutters mounted in said head; a plunger mounted in said bore and adapted to co-act with said cutters so as to move them radially inwardly 60 and outwardly; elastic means for actuating said plunger; means associated with said tool and designed to lock said plunger in forward position so as to hold said cutters in outward position, comprising a keeper 65 mounted on said body and provided at its

inner end with a spiral cam-face; a lever pivoted to said body and operating through slots formed therein which open into the bore thereof, said lever extending through a slot formed in said plunger and normally 70 resting in contact with the top of said cam-face; means interposed between said plunger and said lever whereby said plunger is held in forward position; means co-acting with said keeper and adapted to be moved longitudinally of the tool as said means comes in 75 contact with the work so as to rotate said keeper to move the top of said cam-face past said lever to release said lever and unlock said plunger and permit of the collapse of 80 said cutters through the action of said elastic means, and means whereby the position of said keeper can be adjusted longitudinally of said tool.

3. A tool of the class described comprising 85 a bore-provided body provided with a head having a chamber extending longitudinally thereof; a plurality of cutters mounted in said head; a plunger mounted in said bore and adapted to co-act with the said cutters 90 so as to move them radially inwardly and outwardly; elastic means for actuating said plunger; means associated with said tool and designed to lock said plunger in forward position, so as to hold said cutters in 95 outward position, comprising a keeper mounted on said body and provided at its inner end with a spiral cam-face; a lever pivoted to said body and operating through slots formed therein which open into the 100 bore thereof, said lever extending through a slot formed in said plunger and normally resting in contact with the top of said cam-face; means interposed between said plunger and said lever whereby said plunger is held in forward position; a cam-sleeve mounted 105 on said body and provided with a slot formed of two portions of substantially the same length, which portions occupy substantially the same angle to the longitudinal 110 axis of the tool, one end of one of said slot-portions having sides which extend substantially parallel with the axis of said cam-sleeve, and the said cam-sleeve being further provided with a circumferential inner 115 groove into which the portions of said slot open; a stud carried by said keeper and designed at times to rest in said circumferential groove; a stop mounted in said circumferential groove which normally rests 120 against said stud, and a tripping-plate carried by said cam-sleeve, the same designed to be brought into contact with the work so as to move said cam-sleeve longitudinally to move said cam-stop out of contact with the 125 stud to permit said stud to co-act with one of the portions of said slot and so cause said keeper to rotate on said body so as to effect the unlocking of the tool to permit of the collapse of the cutters, as set forth. 130

4. A tool of the class described comprising a bore-provided body provided with a head having a chamber extending longitudinally thereof; a plurality of cutters mounted in said head; a plunger mounted in said bore and adapted to co-act with said cutters so as to move them radially inwardly and outwardly; elastic means for actuating said plunger; means associated with said tool and 5 designed to lock said plunger in forward position so as to hold said cutters in outward position, comprising a keeper mounted on said body and provided at its inner end with a spiral cam-face; a lever pivoted to said body and operating through slots formed therein which open into the bore thereof, said lever extending through a slot formed in said plunger and normally resting in contact with the top of 10 said cam-face; means interposed between said plunger and said lever whereby said plunger is held in forward position, a cam-sleeve mounted on said body and provided with a slot formed of two portions of substantially the same length, which portions occupy substantially the same angle to the longitudinal axis of the tool, one end of one 15 of said slot-portions having sides which extend substantially parallel with the axis of 15 said cam-sleeve, and the said cam-sleeve being further provided with a circumferential inner groove into which the portions of said slot open; a stud carried by said keeper and 20 designed at times to rest in said circumferential groove; a stop mounted in said circumferential groove normally resting against a tripping plate adjustably carried by said cam-sleeve, the same designed to be brought 25 into contact with the work so as to move 85 said cam-sleeve longitudinally to move said cam-stop out of contact with the said stud to 90 permit said stud to co-act with one of the portions of said slot and so cause said keeper to rotate on said body so as to effect the unlock- 95 ing of the tool to permit of the collapse of the cutters, as set forth. 6. In a tool of the class described, in combination a bore-provided body; a plunger mounted therein; a plurality of cutters adapted to co-act with said plunger so that as said plunger is moved longitudinally of 100 said body, the cutters will be expanded or contracted; means mounted in said body and designed to hold said plunger in forward position to keep said cutters expanded; elastic means exerting energy to withdraw said 105 plunger to collapse said cutters; a keeper mounted on said body and provided with a spiral cam-face against the top of which said holding means normally rests, and means rotating with said body whereby 110 through the coaction therebetween and the work, said keeper will be moved around the axis of the tool so as to permit said holding means to escape from the top of said cam-face to the lowest part thereof so as to permit said elastic means to collapse said cutters.
5. A tool of the class described comprising a bore-provided body provided with a head having a chamber extending longitudinally thereof; a plurality of cutters mounted in said head; a plunger mounted in said bore and adapted to co-act with said cutters so as to move them radially inwardly and outwardly; elastic means for 5 actuating said plunger; means associated with said tool and designed to lock said plunger in forward position so as to hold said cutters in outward position, comprising a keeper mounted on said body and pro- 115

PETER JARDINE.
